Primary Examiner — David Muller(74) *Attorney, Agent, or Firm* — Eitan, Mehulal & Sadot(57) **CLAIM**

The ornamental design for a medical syringe extension device, as shown and described.

DESCRIPTION

FIG. 1 is a perspective view of the medical syringe extension device in a retracted position;
FIG. 2 is a right side view thereof;
FIG. 3 is a left side view thereof;
FIG. 4 is a front view thereof;
FIG. 5 is a rear view thereof;
FIG. 6 is a top view thereof;
FIG. 7 is a bottom view thereof;
FIG. 8 is a perspective view of the medical syringe extension device in an extended position;
FIG. 9 is a right side view thereof;
FIG. 10 is a left side view thereof;
FIG. 11 is a front view thereof;
FIG. 12 is a rear view thereof;
FIG. 13 is a top view thereof; and,
FIG. 14 is a bottom view thereof.
